(57) **CLAIM**

The ornamental design for a storage container, and the container lid, as shown.

DESCRIPTION

FIG. 1 is a front isometric view of the storage container, and the container lid, showing my new design.

FIG. 2 is a front view of the storage container thereof;
FIG. 3 is a back view of the storage container thereof;
FIG. 4 is a left-side view of the storage container thereof;
FIG. 5 is a right-side view of the storage container thereof;
FIG. 6 is a top plan view thereof;
FIG. 7 is a bottom plan view thereof; and,
FIG. 8 is an isometric expanded view of the storage container with lid removed thereof.
